GLOVE AND MITTEN DRYER

Charles E. Jennings, Jr., 4020 Simon Road,
Youngstown, Ohio

Filed Aug. 14, 1961, Ser. No. 66,325

Term of patent 14 years

(Cl. 49—1)

FIG. 1

FIG. 2

FIG. 3

FIGURE 1 is a perspective view of a glove and mitten dryer, showing my new design;

FIGURE 2 is a front elevational view thereof;

FIGURE 3 is an end elevational view thereof.

The rear and side not shown are like the respective front and side shown except that the dial is omitted.

The characteristic feature of my design for the glove and mitten dryer reside in the specific shape of the wire forms associated with the heater openings in the top of the dryer base as shown.

I claim:

The ornamental design for a glove and mitten dryer, as shown and described.
